VESTIBULE DIAPHRAGM SECURING DEVICE

Einar F. Nelsen, West Allis, Wis.

Application June 14, 1952, Serial No. 293,610

2 Claims. (Cl. 105—20)

This invention relates to vestibule diaphragms for railway passenger cars, and has for its principal object to hold the lower, intermediate portions at each side in proper relation to the foot plates to maintain the passage-way closed.

Generally speaking, this is accomplished by providing brackets at each side of the intermediate portion of the diaphragm hooking beneath the foot plates to hold the diaphragm down, and connected together to hold the diaphragm sides against objectionable bulging.

In the drawings showing the preferred embodiment of the invention:

Fig. 1 is a perspective of a fragment of a vestibule end of a passenger car, parts being broken away;

Fig. 2 is a horizontal section taken on the line 2—2 of Fig. 1;

Fig. 3 is a side elevation showing the hooked bracket and its relation to the vestibule and the foot plates; and

Fig. 4 is a perspective view of one of the hooked brackets.

But these diagrammatic drawings and the corresponding description are used for the purpose of disclosure only, and are not intended to impose unnecessary limitations on the claims.

In the drawings, there is shown a familiar folded or pleated, flexible vestibule diaphragm 10 extending between the vestibule posts 11 and the side legs 12 of an arched face plate connected at their lower ends to a buffer plate 13 carried by side and center stems 14 and 15.

The buffer plate 13 is equipped with a buffer foot plate 16 running under andlapping the vestibule platform or foot plate 17 to form a tread for the vestibule passageway. The means for supporting the vestibule and its face plate are familiar, as is also the yielding as the cars move along the track about curves, etc.

The diaphragms are necessarily quite flexible in order to accommodate the necessary movement of the face plates with respect to the car.

Bulging outwardly or toward the side of the car is unobjectionable except near the foot plates, where bulging results in openings between the bottom of the vestibule legs and the foot plates or platform, through which air, dust, snow, etc., pass.

To prevent the objectionable bulging and to insure constant closure between the bottom of the vestibule and the tread plates, this invention provides each side of the vestibule with hooked brackets, generally indicated by B, riveted or otherwise secured to the vestibule diaphragm at 18 and hooking around the overlapping edges of the plates 16 and 17, as shown particularly in Figs. 1 and 3.

2

The hooked brackets B at each side are cross-connected by a spring or springs 19 and tie rods 20 (Figs. 1—3), which insure that the legs of the vestibule on opposite sides of the passageway are kept within proper limits for tight closure adjacent to the foot plates.

According to this preferred embodiment, the hooked brackets are provided with channels 21 which receive pleats or folds 22 on the vestibule diaphragm, to which they are secured by the rivets 18. The brackets taper as indicated at 23 and turn into inwardly directed hooks 24, as best shown in the drawings.

Preferably as indicated, the brackets are made of sheet metal, cut or stamped out substantially as shown.

The overlapping foot plates 16 and 17 are here provided with a rubber mat 25 on the order of $\frac{1}{4}$ " thick, secured at the vestibule door or thereabouts, and overlying the foot plates to provide a non-slip walk.

I claim:

1. In a vestibule diaphragm assembly for railway cars or the like of the type including a face plate resiliently supported a given distance from the car end, a collapsible, vertically pleated diaphragm extending between said face plate and the car end, and overlapping foot plates providing a floor for said assembly, with the bottom margin of the diaphragm positioned above said foot plates and in close proximity thereto, the combination therewith of means for maintaining said bottom margin continuously in close sealing contact with said foot plates, said means comprising a bracket secured to an intermediate portion of the diaphragm adjacent its lower margin and having a hooked portion of said bracket extending outwardly around said foot plates and then inwardly and under said foot plates and in firm contact with the under face of said foot plates to thereby hold the diaphragm in sealing engagement with the upper face of said foot plates.

2. In a vestibule diaphragm assembly for railway cars or the like of the type including a face plate resiliently supported a given distance from the car end, a collapsible, vertically pleated diaphragm extending between said face plate and the car end, and overlapping foot plates providing a floor for said assembly, with the bottom margin of the diaphragm positioned above said foot plates and in close proximity thereto, the combination therewith of means for maintaining said bottom margin continuously in close sealing contact with said foot plates and for resiliently resisting outward bulging of the lower portion of said diaphragm, said means comprising a bracket secured to an intermediate portion of the diaphragm adjacent its lower margin and having a hooked portion of said bracket extending outwardly around said foot plates and then inwardly and under said foot plates and in firm contact with the under face of said foot plates to thereby hold the diaphragm in sealing engagement with the upper face of said foot plates, and spring means biasing said bracket toward the center line of the car.
